WIRE STRIPPER

Gene R. Stephenson, Sheridan, Oreg.

Application May 31, 1950, Serial No. 165,281

5 Claims. (Cl. 30—91)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a wire stripper for removing the covering or insulation from covered wires.

In using electrical conductors, particularly flexible wire conductors such as are commonly used in telephone lines, telegraphy, etc., there is a continuous need for removing the insulation covering from the wire.

The primary object of the invention is to provide a means for facilitating the removal of insulating material from electrical conductors at places where splices or connections are to be made.

Other objects and advantages will become apparent from the following description, in which:

Fig. 1 is a front elevational view of a pair of pliers having incorporated therein a preferred form of stripping means and showing an insulated wire being drawn between the stripping means;

Fig. 2 is a front elevational view of a modified form of my invention; and

Fig. 3 is an enlarged elevational view of the stripping means of Fig. 1, the insulated conductor being shown in section for reasons of clarity.

In the drawing, a pair of pliers 11 includes crossed levers 13, 15, pivoted about a pivot pin 16, the forward ends of which levers cooperate to provide coacting jaws, each of said jaws having flattened knurled portions 17. The rear ends of the levers 13, 15 form handles 19, 21 as shown.

The inner faces of the levers 13, 15 are provided respectively with recesses 23, 25, in which recesses are mounted, respectively, rotatable cutting members 27, 29 which serve as means for cutting, abrading or marring the insulation 31 of an insulated cable 33. Extending through the recesses 23, 25 are posts 35, 37 upon which the cutting members 27, 29, respectively, freely rotate as hereinafter described. Each of said cutting members 27, 29 is a cylinder, the lateral surface of which is provided with a helically disposed cutting edge 39, similar to a screw thread. As is seen in Fig. 1, the cutting members 27, 29 are substantially parallel to each other when the pair of pliers 11 are in operating position.

In the form of my invention shown in Figs. 1 and 3, the two cutting edges 39, of the two cutting members 27, 29 comprise right hand threads. However, if desired, both cutting members 27, 29 could have left hand cutting threads.

In Fig. 2, there is shown a modified form of

2

my invention wherein the cutting edges or screw threads 39 of the cutting members 27, 29 have opposite direction; that is, the left hand member 27 has a left hand thread, and the right hand member 29 has a right hand thread.

In use, the handles 19, 21, are drawn apart (as shown in Fig. 2) and the cable 33, from which a part of the insulation 31 is to be removed, is placed between the cutting members 27, 29. The handles 19, 21 are then moved toward each other so that the cutting edges 39 firmly grip said cable. One end of the cable 33 is then grasped and it is drawn between said cutting members 27, 29 causing said members to rotate. In the course of such rotation, the insulation 31 will be cut and abraded by the cutting edges 39. Where the cutter is to be used generally on a particular size of cable, it is desirable that the spacing between the cutting edges 39 of the members 27, 29 be at least as great as the diameter of the conductor of the cable. However, in a wire stripper for use with conductors of different sizes, the depth of cut or amount of abrasion of insulation 31 can be readily controlled by the pressure applied on handles 19, 21.

When the wire stripper is so made that the rotatable members 27, 29 have cutting edges that are either both left handed threads or both right handed threads, an insulated wire drawn through the tool will not ride up or down the threads, but will remain fixed at any point between the rotatable members 27, 29. By twisting the wire in its travel through the tool, all surfaces of the insulation 31 will be thoroughly and completely cut and abraded. Removal of the cut portion of the insulation can be easily and quickly accomplished by inserting the cut section of the insulation between the knurled portions 17 of the jaws of the pliers and drawing off said cut portion leaving the exposed conductor for its desired use.

While there has been herein described the preferred embodiments of my invention, it is obvious that modifications and changes may be made without departing from the spirit and scope of my invention. For example, while I have described the edges of the cutting members as being made of helically disposed screw threads, it will be apparent that other types of abrading or cutting surfaces may be utilized. As a means for carrying the cutting members, I have indicated that a pair of crossed levers, such as a pair of pliers, be used. It is to be understood, however, that the invention is not to be limited to such modification as other supporting means for carrying the cutting members may be also utilized.

Having thus described the invention, what is claimed as new is:

1. In a tool for the removal of insulation from wires, the combination of a pair of pivoted crossed levers, and means sustained by said levers for removing the insulation from wires, said means comprising cutting members rotatably sustained respectively by said levers in coacting relationship, each of said members having a helically positioned cutting edge thereon.

2. A tool of the type described in claim 1 where-
in the cutting edges of said rotatable members have opposite directions of pitch with respect to each other.

3. In a tool for the removal of insulation from wires, the combination of a pair of pivoted crossed levers, the inner faces of said levers being pro-
vided with mutually opposing recesses, a pin dis-
posed in each of said recesses and a cutting mem-
ber rotatably carried by each of said pins, each
of said members having a substantially helically
positioned cutting edge, said edges of both mem-
bers having the same direction of pitch.

4. A tool of the type described in claim 1,

wherein the cutting edges of said rotatable mem-
bers have the same direction of pitch.

5. A tool for the removal of insulation from an insulated wire, comprising in combination a pair of rotatably mounted cutting members, each of said members consisting of a cylindrical body having a substantially helically positioned edge thereon for abrading and cutting the insulation of said wire and means for urging said mem-
bers toward each other.
